UNITED STATES PATENT OFFICE.

CHARLES C. KLINGAMAN, OF WINTERSET, IOWA.

MAIL-BOX.

1,150,039.

Specification of Letters Patent.

Patented Aug. 17, 1915.

Application filed February 24, 1914. Serial No. 820,380.

To all whom it may concern:

Be it known that I, CHARLES C. KLINGAMAN, a citizen of the United States, residing in Winterset, county of Madison, and State 5 of Iowa, have invented a new and useful Improvement in Mail-Boxes, of which the following is a specification.

The object of my invention is to provide a mail box, particularly adapted for rural 10 mail routes, in which a false bottom will be provided near the top of the box when the cover is raised but when the cover is closed the false bottom collapses and drops the mail into the box.

15 This construction provides a box which cannot be pilfered or tampered with because the raising of the cover closes the box above the mail which has been placed therein and deposited in the bottom in the manner set forth.

20 My invention consists of certain details of construction hereinafter set forth, pointed out in my claims, and illustrated in the accompanying drawings, in which—

25 Figure I shows a perspective view of the upper portion of my mail box; Fig. II shows a sectional view of my mail box, a portion of the body being broken away; and Figs. III and IV show detail views of the 30 side door of my mail box.

Referring to the accompanying drawings the reference numeral 10 is used to indicate the body portion of my mail box and the numeral 11, the hinged cover therefor, an outgoing mail receptacle 12 being provided thereon, as shown. Rigidly secured to the inside of the cover slightly above its hinged connection 13, and extending downwardly therefrom parallel with and close against 35 the rear wall of the box, is a metal, or like, member 14, the length of which is not as great as the width of the box. This member is practically as wide as the length of the box and moves with the cover. Hinged to the front of the box, on the inside thereof, 40 is a second metal, or like, member 15 the width of which is practically as great as the length of the box. These two members, 14 and 15, are joined on each side of a rod, or arm, 16, loosely secured near the upper end of the member 14 and depending slightly downward on an angle to a loose connection with the member 15. The point at which it 45 is secured to the member 15 is determined by 50 such mathematical precision as will permit

the two members 14 and 15 to pass each other in their upward movement, their upper position being shown by the dotted lines in Fig. II.

In practical operation the parts are in the 60 position shown in Fig. II when the cover is closed. The opening of the cover causes the member 14 to be elevated and this action moves the rod 16 rearwardly thus elevating the member 15. When the cover has reached 65 its upward limit of movement the rods and members 14 and 15 are in the position shown by the dotted lines in Fig. II, and as the members 14 and 15 are of such added length as will be greater than the width of the box, 70 a perfect false bottom, or tray, on which mail may be deposited is provided. It is obvious that the closing of the lid drops the members 14 and 15 to their positions as shown in the full lines in Fig. II and thus 75 drops the mail to the base of the box. The mail is taken therefrom through the door 17, which is designed to be locked against intrusion.

Having thus described my invention what 80 I claim and desire to secure by Letters Patent of the United States is:

1. A mail box comprising a body portion and cover hinged thereto; a depending member hinged to the inside of the front of the 85 box and near the top thereof; a second member fixed to the cover and extending downwardly therefrom along the inside of the back of the box; rods between the said members, said rods having loose connections at 90 their ends with said members and so arranged that the opening of the cover carrying with it the member near the rear of the box, elevates the member hinged to the forward part of the box, the two members passing 95 each other and assuming a horizontal plane overlapping each other.

2. A mail box including a body portion and a hinged closure, a depending member hinged to the inside of the front of said 100 body portion near its upper edge, a depending second member fixed to said closure, near its hinged edge, rods between said members, having loose connection therewith, at the rod ends, said rods being arranged with 105 respect to said depending members and closure whereby, by opening the latter, the former will be moved upwardly and past each other, and caused to assume a horizontal position overlapping each other.

3. In combination with a mail box having a hinged closure, a member hinged to the front of the box, a second member rigidly secured to the cover so as to move therewith, and means connected to the second member and to the first member slightly above the cover hinge whereby upon opening of the cover said members will be caused to overlap, and said means will occupy a horizontal position in a plane parallel to the plane in which the members overlap.
4. In combination with a mail box hav-

ing a hinged closure, a member hinged to the front of the box, a second member rigidly secured to the cover so as to move therewith, and a link connected to the two members, said link when the cover is open being disposed entirely below the top of the box.

CHARLES C. KLINGAMAN.
